FRANK B. EILERS AND NESTOR FRIES, OF FORT WAYNE, INDIANA, ASSIGNEES TO
TOKHEIM OIL TANK AND PUMP COMPANY, A CORPORATION OF INDIANA.

DISPENSING-PUMP MECHANISM.

Application filed July 10, 1922. Serial No. 573,889.

To all whom it may concern:

Be it known that we, FRANK B. EILERS and NESTOR FRIES, citizens of the United States of America, and residents of Fort Wayne, in the county of Allen and State of Indiana, have invented certain new and useful Improvements in Dispensing-Pump Mechanism, of which the following is a specification.

10 This invention relates to improvements in dispensing pump mechanism, and the objects thereof are: first, to provide a simple mechanism for actuating a reciprocal pump member selectively in opposite directions at different speeds under control of an operating crank; and second, to provide an externally operable enclosed stop mechanism for limiting the discharge stroke of the pump member selectively at different stages and to 20 provide also an indicating means therefor.

These objects are accomplished by the construction illustrated in the accompanying drawings in which:—

Fig. 1 is a fragmentary elevation of a 25 pump stand in section and including actuating mechanism for the reciprocating pump member and for adjusting the stop mechanism.

Fig. 2 is an elevation projected from Fig. 30 1, a portion being broken away to disclose the stop mechanism;

Fig. 3 is a detail view showing a cross section of the pump member and the stops therefor on the line 3— of Fig. 2;

Fig. 4 is a front elevation of the upper 35 portion of the pump stand upon an enlarged scale, with portions broken away;

Fig. 5 is an enlarged detail view showing a cross-section of the stops on the line 5— 40 of Fig. 2; and

Fig. 6 is a fragmentary elevation projected from Fig. 5.

The characters appearing in the description refer to parts shown in the drawings 45 and designated thereon by corresponding characters:

The invention comprises a hollow pump stand 1 having therein a reciprocal pump member 2 consisting of a rack of the type 50 ordinarily used for actuating a pump. In the upper part of the stand is contained a back gearing consisting of a shaft 3 having a pinion 4 and toothed wheel 5 fixed thereon, the pinion having operable relation with 55 the rack. Also, in the stand is arranged a

crank-shaft 6 adapted to have both rotary and longitudinal movement in the bearings 7 and 8. Upon the crank-shaft are loosely mounted two clutch-actuated gears, 9 and 10, that have constant meshing engagement 60 respectively with the rack 2 and the toothed wheel 5. The clutch gears are spaced apart and positioned with their toothed ends oppositely disposed. The gear 9 has a groove 65 11 in its hub into which extends a fixed plate 12 which prevents longitudinal movement of the gear, and the gear 10 has a flange 13 that projects over the side of the wheel 5 and serves to prevent the gear 10 from having longitudinal movement. 70

Upon the crank-shaft, between the clutch gears, is fixed a clutch member 14 that is adapted to selectively engage the clutch gears 9 and 10 accordingly as the crank-shaft 6 is longitudinally positioned so that 75 said gears may be severally actuated when the crank-shaft is rotated. The ends of the clutch member 14 and the ends of the respective clutch gears adjacent thereto are saw-toothed, the slant of the teeth on said member and gears being such that when either gear is engaged by said member movement may be imparted thereto by rotating the crank-shaft in one direction, and so that said member will become disengaged and inoperative when the crank-shaft is oppositely rotated. For instance: When the crank-shaft is pushed in and turned clockwise, the gear 9 will be engaged and driven by the member 14; when the crank-shaft is pulled outwardly and turned clockwise the gear 10 will be engaged and driven by said clutch member; and when the crank-shaft is rotated backwardly the clutch member will 80 idly rotate with the crank-shaft, out of engagement with the gears. 85

Within the stand is a shaft 15 rotatably mounted in a position parallel with and adjacent to the rack 2, the upper end of the shaft extending into a bearing 16 in the upper end of the stand, and upon said shaft adjacent the bearing is fixed a flange 17 the hub of which contacts with the lower end of the bearing so that upward movement thereof is positively limited. 90

In the flange 17 are adjustably secured a concentric series of stops 18, 19, 20, 21 and 22 respectively, each of which consists of a rod, the upper end of which has threaded relation with the flange and depends there- 100 105 110

from in parallel relation with the shaft 15. The stops vary in length and each is provided with a fixed nut 23 by which it may be adjustably turned in the flange.

5 Guides 24 are provided on the shaft 15 for holding the stops in proper order. A notched collar 25 is mounted on the shaft 15 and is vertically movable thereon and adapted to engage the nut 23 of each stop and 10 thereby prevent the stops from being turned in the flange 17. The collar has a set screw 26 for securing it in place on the shaft and the stand has a sealed door 27 adjacent the collar, which, when opened admits of making 15 readjustments of the stops. By turning the shaft 15 upon its axis the stops may be severally positioned into the path of a lug 28 that projects from the rack 2 near its lower end, so that the upward stroke of the 20 rack is thereby limited more or less accordingly.

In the lower part of the stand is a casing 29 having a glazed sight opening 30 and containing a rotatable flange 31 which 25 is mounted upon a shaft 32 that extends centrally through the casing. The shaft has upon its front end, exterior of the casing, an operating lever 33, and upon its inner end a miter gear 34 that meshes with a similar miter gear 35 which is fixed upon a vertical spindle 36 in the stand. The lower end of the shaft 15 is operatively connected with the spindle 36 by means of a sleeve 37 so that as the spindle is turned the shaft 30 will be likewise turned and the stops thereby moved accordingly into the path of the lug 28 on the rack. In the casing is a spring-pressed detent pin 38 that bears against the rear face of the flange 31, the 35 flange being notched to receive the detent member 38 so as to be frictionally held in adjusted positions to which it is turned by manipulating the operating lever 33. Upon the disk are displayed characters 39 that 40 are brought successively into position at the sight opening in the casing, which characters are significant of the respective stops, the particular character appearing at the sight opening being significant of the particular stop that is positioned for engagement by the lug on the rack. Each character is also significant of the quantity of liquid that is dispensed upon an operation of the pump member under the limitation 45 of the corresponding stop.

In utilizing the invention the rack is connected up with the plunger of a displacement pump (not shown) of the reciprocal type adapted to deliver liquid in varying quantities according to the extent of movement of its plunger as in the usual practice, and the various stops are turned in the flange to effect respective adjustments thereof so that the rack will be accordingly 60 limited at corresponding stages of its stroke, 65

and thus insure accuracy of the various quantities of liquid to be discharged by the pump. The notched collar is then slid upwardly upon the shaft 15 so as to engage all of the nuts on the stops, and is secured in engaging position by tightening the set-screw and closing the door. In operating the invention, the lever 33 is turned until the character on the dial that is significant of the quantity of liquid desired appears at the sight opening. For instance: In an apparatus having a five gallon capacity, the full stroke of the pump member being required, the lever is turned so that the stop 18 is positioned in the path of the lug on the rack, which admits the full stroke of the pump; or, if a lesser quantity is required, the lever is turned to such position as to bring the desired stop into the path of the lug according to the quantity of liquid desired. The crank-shaft is then drawn outwardly and rotated, clockwise, causing the clutch member to engage and drive the clutch-gear 10, thus imparting upward movement to the rack through the medium of the back gearing until the movement of the rack is interrupted by the stop mechanism. The crank-shaft is then pushed inwardly and turned, clockwise, so that the clutch member is moved from engagement with the clutch gear 10 and into actuating engagement with the clutch gear 9 and causing downward movement on the return stroke of the rack. As the action of the clutch gear 9 is with the same velocity as the crank-shaft, the downward movement of the rack is comparatively faster than its upward movement which is effected through the medium of the back gearing with the incidental additional leverage that is necessary in effecting the upward or discharge stroke of the pump which usually requires greater force than the returning stroke. In this manner the physical force applied to the crank-shaft during the upward and downward strokes of the pump member is more nearly uniform while the return stroke thereof is accelerated.

What we claim is:—

1. In dispensing pump mechanism including a closed stand and rack-bar movable therein and gearing for actuating the rack-bar, a rotatable shaft arranged in the stand parallel with the rack-bar; a flange member fixed on the shaft; a series of stop rods arranged in a concentric series around said shaft, each rod having threaded relation in the flange member thereon, said rods differing in length and being adapted to have engagement with the rack-bar selectively accordingly as said shaft is adjustably turned; guides on said shaft for said rods; means adapted to have sealed adjustment on said shaft and locking engagement with said rods collectively; and means operable from

the exterior of the stand for turning said shaft.

2. In dispensing pump mechanism including a stand and rack-bar movable therein and gearing for actuating the rack-bar, a rotatable shaft arranged in the stand parallel with the rack-bar; a flange member fixed on the shaft; a series of stop rods arranged in a concentric series around said shaft, each rod having threaded relation in the flange member thereon, said rods differing in length and being adapted to have engagement with the rack-bar selectively accordingly as said shaft is adjustably turned; guides on said shaft for said rods; and means adapted to have sealed adjustment on said shaft and locking engagement with said stops collectively.

3. In dispensing pump mechanism including a stand and rack-bar movable therein and gearing for actuating the rack-bar, a rotatable shaft arranged in the stand parallel with the rack-bar; a flange member fixed on the shaft; and a series of stop rods arranged in a concentric series around said shaft, each rod having threaded relation in the flange member thereon, said rods differ-

ing in length and being adapted to have engagement with the rack-bar, selectively accordingly as said shaft is adjustably turned. 30

4. In dispensing pump mechanism including a closed stand and rack-bar movable therein and actuating mechanism for the rack-bar; a stop mechanism within the stand comprising a shaft arranged parallel with the rack-bar; a flange member fixed on the shaft; a series of stop rods arranged in a concentric series around said shaft, each rod having a fixed nut thereon and threaded relation in said flange member, said rods differing in length and being adapted to have engagement with the rack bar selectively accordingly as said shaft is adjustably turned; sealing means for securing said nuts collectively; and means operable from the exterior of the stand for turning said shaft. 45
